UNITED STATES PATENT OFFICE.

MARTIN FISCHER, OF ZURICH, SWITZERLAND, ASSIGNOR TO FISCHER MOTOR CORPORATION, OF NEW YORK, N. Y., A CORPORATION OF NEW YORK.

INTERNAL-COMBUSTION ENGINE.

1,222,615.

Specification of Letters Patent.

Patented Apr. 17, 1917.

Application filed March 19, 1915. Serial No. 15,676.

To all whom it may concern:

Be it known that I, MARTIN FISCHER, a citizen of Switzerland, residing at Zurich, Switzerland, have invented certain new and useful Improvements in Internal-Combustion Engines, of which the following is a specification.

My invention relates to internal combustion engines of the slide valve type.

10 More particularly my invention relates to a modification of, or an improvement upon, the type of slide valve engine shown in my Patent No. 1,103,901, dated July 14, 1914, and entitled "Combustion engine," although 15 the herein disclosed improvements may also be applied advantageously to other types of slide valve engines.

20 In my prior patent just referred to the operative cycle of the engine is controlled by a pair of oppositely disposed crescent sectioned valves embedded in the cylinder walls, between the cylinder and the piston, and actuated by suitable gears driven from the main shaft so as to open and close suitable 25 fuel and exhaust ports in proper sequence.

It is the object of my present invention to 30 simplify the construction disclosed in my prior patent by eliminating one of the slide valves thereof and so disposing the ports controlled by said slide valve upon the other side of the cylinder with relation to the other slide valve, that the same operative cycle may be controlled by one valve instead of 35 two. This improvement lessens the number of parts and, in this and other ways, obviously simplifies and cheapens the construction and decreases the wear and tear. Other advantages also result as will be detailed below.

40 By having but one slide valve upon one side of the cylinder my improved engine as herein disclosed lends itself readily to the construction of multi-cylinder engines of V type, the cylinders being connected together 45 at their bases, preferably integrally in a single casting, and diverging upwardly so that the cranks may operate on a common crank shaft. In this type of construction the single valves of each cylinder face one another 50 on opposite inner sides of the V thus making the valves and ports extremely accessible for adjustment and repair.

A further object of my invention is to arrange the intake and exhaust ports, controlled by the single valve, in juxtaposition;

this permits a heat exchange to take place between the intake mixture and the exhaust gases, the former being heated before combustion and the latter being cooled after combustion. This heating of the intake 60 gases causes them to be burned more efficiently while cooling of the exhaust gases tends toward the same result and, furthermore, aids in cooling the engine parts so as to enhance their durability and freedom of 65 operation.

A still further object of my invention is to so arrange the single valve of each of two adjacent cylinders, that they may be driven in proper sequence by a single cam or its 70 equivalent.

A still further object of my invention is to provide an arrangement of slide valve and cooling chamber which will insure 75 against over-heating of the valve and its consequent breakage in the neighborhood of the ports.

Other objects of my invention will appear as the specification proceeds.

Referring to the drawings, which represent a two cylinder internal combustion engine embodying my improvements, Figure 1 is a vertical section taken along the irregular line 1-1 of Fig. 2; Fig. 2 is a horizontal section, part plan, taken along the line 85 2-2 of Fig. 1; Fig. 3 is a vertical section (of the same character as that of Fig. 1) through the end of the valve and corresponding part of the cylinder wall, showing the position of the valve and cylinder ports 90 for intake; and Fig. 4 is a section, similar to Fig. 3, but showing the position of the ports for either the compression or explosion stroke.

In the drawings, the cylinders 1, 1' are 95 mounted upon a common crank case 2 in the usual way. A single crescent shaped valve 3, 3' of substantially the entire length of the cylinder, is embedded in each cylinder wall between it and its piston and is adapted to be 100 slid up and down, as will be hereinafter explained. This crescent shaped valve preferably subtends a little less than 90° of an arc and is of the same general character as is disclosed in my prior patent above referred to.

Both pistons 4, 4' of the two cylinders are connected by connecting rods 5, 5" to cranks 6-6', 180° apart, of a common crank shaft 7. An intake port 8, (8', not shown) and 110

an exhaust port 9, 9' are formed as transverse slits closely adjacent to one another in each cylinder wall and the valve 3, 3', is provided with a similar single slot 10 (10', not shown) near its upper end.

- 5 The two valves of the two cylinders are so disposed that vertical radial planes passing through the center of each valve and the axis of its cylinder make equal angles 10 with the plane passing through said axes and meet one another at an angle of 90°. A rotatable cam 11 is placed with its axis coincident with the line of intersection of these two radial planes and the periphery of this 15 cam is provided with a cam groove 12 with which the pin 13 of each slide valve is engaged. This cam 11 is provided with a spiral gear 14, in mesh with a spiral worm gear 15 which is itself driven, by a chain 16, 20 from a sprocket 17 which is mounted upon the crank shaft 7. These several gears are so dimensioned that one complete revolution of the cam corresponds with two complete revolutions of the crank shaft and therefore 25 with two complete strokes of the piston.

In addition to the usual hollow walls of the cylinder for the circulation of cooling water the cylinder head is so arranged as to provide an insert or channel like portion 18, 30 which closely engages the upper inside surface of the valve. This channel portion 18, together with that portion of the circulating system of the cylinder wall which engages the opposite side of the upper part of the 35 valve, constitutes what may be termed a cooling pocket for the valve end.

A spark plug 19 provides for ignition in the usual way.

The operation of my improved engine is 40 as follows:

As shown in Figs. 1 and 2 the piston 4 has just completed its downward stroke, due to the explosion of the combustion gases above it, and is rising on the exhaust stroke. The 45 valve 3 has its port 10 in register with the exhaust port 9, and remains in such position until the piston has nearly completed its upward exhaust stroke, by which time the cam 12 will have turned sufficiently to bring the 50 pin 11 in that part of the cam groove 13 which slopes suddenly downward. This will cause the valve 3 to be slid downwardly until its port 10 comes into register with the intake port 8 just as the piston 3 starts on its 55 downward suction stroke. At the bottom of the suction stroke the cam groove 13 rises slightly (see dotted lines on cam, Fig. 1) and thereby raises the valve until the port 10 is covered by the septum 20 which separates 60 the intake and exhaust ports 8 and 9 (Fig. 4); this position is retained during the following upward compression stroke. As the piston reverses at the top of its stroke, the explosive mixture is fired through the spark 65 plug 19 and the power stroke ensues. Dur-

ing this power stroke the valve remains in the position shown in Fig. 4 until and just after the end of the stroke when the cam again raises the valve and it and the ports again have the position shown in Figs. 1 70 and 2 and the cycle is complete.

The description just given of the operative cycle belonging to cylinder 1, valve 3 and piston 4 applies with equal accuracy to the adjacent cylinder 1', valve 3' and 75 piston 4', except that each step of this second cycle takes place later by a period of time represented by one-half a revolution of the crank shaft. This is clear when it is observed that the crank belonging to the second 80 cylinder is always one-half a revolution behind the crank belonging to the first piston and that furthermore, the cam groove 12 advances from the first cylinder to the second and holds the valve 3' of the second 85 cylinder in exactly the same position at all times as it held the valve of the first cylinder at an earlier period of time corresponding to one-quarter a revolution of the cam, which is itself as previously explained arranged to rotate at just one-half of the speed 90 of the crank shaft.

While I have described my invention as embodied in a two cylinder engine, it is clear that one cylinder may be omitted within the 95 scope of the invention. It is also clear that I may apply my improvements to an engine embodying any number of pairs of cylinders, each pair being operated by a common cam. Or I may embody a single valve part of my 100 invention in an engine having an odd number of cylinders.

I have shown the valve regulating cam as driven from the crank shaft by a chain and I prefer this type of drive. However, any 105 mechanism which permits the cam to be driven in correspondence with the movements of the piston would serve equally well. It should also be clear that my improvements herein described are not necessarily 110 restricted to valves of crescent shaped section and that the section of the valves has no fundamental or essential relation with said improvements.

Other modifications may be made within 115 the scope of the invention.

I disclaim herein any structures disclosed in the French patent granted to me, No. 428,733, dated September 6, 1911.

Having described my invention, I claim: 120

1. In an internal combustion engine having two parallel cylinders and a pair of pistons connected 180° apart to a common crank shaft, a pair of axially adjacent ports for each cylinder, a longitudinally slidable 125 valve for each cylinder between the cylinder and the piston and having a port to register with either cylinder port, a single cam having its axis parallel to the axes of the cylinders and arranged to actuate both 130

- valves, and means for driving said cam in correspondence with the crank shaft for similarly setting the two valves when their pistons are in corresponding positions.
- 5 2. In an internal combustion engine having two parallel cylinders and a pair of pistons connected 180° apart to a common crank shaft, a pair of axially adjacent ports for each cylinder, a longitudinally slideable 10 valve for each cylinder between the cylinder and the piston and having a port to register with either cylinder port, a cam having its axis parallel to the axes of the cylinders and a peripheral groove common to and 15 engaged with both valves, and means for driving said cam in correspondence with the crank shaft.
3. In an internal-combustion engine having two parallel cylinders and a pair of 20 pistons connected 180° apart to a common crank shaft, a pair of axially adjacent ports for each cylinder, a longitudinally slideable valve for each cylinder between the cylinder and the piston and having a port to register with either cylinder port, each valve having 25 a projecting pin, a cam provided with a groove with which both of said projecting pins are directly engaged for actuating the valves, and means for driving said cam in correspondence with the crank shaft.

axis parallel to the axes of the cylinders and provided with a groove with which both of said projecting pins are directly engaged so as to actuate the valves, and means for 30 driving said cam in correspondence with the crank shaft.

4. In an internal combustion engine having two parallel cylinders and a pair of pistons connected 180° apart to a common 35 crank shaft, a pair of axially adjacent ports for each cylinder, a longitudinally slideable valve for each cylinder between the cylinder and the piston and having a port to register with either cylinder port, each valve having 40 a projecting pin, a cam provided with a groove with which both of said projecting pins are directly engaged for actuating the valves, and means for driving said cam in correspondence with the crank shaft. 45

In testimony whereof I have hereunto set my hand in the presence of two subscribing witnesses.

MARTIN FISCHER.
